COSMETIC OR PHARMACEUTICAL ASSEMBLY, INCLUDING A MIRROR

Hedwig Schwarz, née Korányi, Vienna, Austria,
and Bernhard Köllisch, Nürnberg, Germany,
assignors to Bernhard Köllisch, Nürnberg, Germany

Application January 20, 1950, Serial No. 139,757

Claims priority, application Austria
January 22, 1949

4 Claims. (Cl. 132—79)

1 This invention relates to a cosmetic stick or pencil, more particularly to a lip stick, eyebrow pencil or the like. For the sake of brevity, the term "lip stick" as hereinafter used is meant to include all types of cosmetic pencils.

It is the object of the invention to provide a combination of a lip stick or the like with a mirror.

Another object of the invention is to arrange the mirror in such a way that it forms in its operative position an extension of the casing while in its non-operative position it lies against the longitudinal side of the casing and can be locked in its position by means of the lip stick carrier.

Another object of the invention is to provide an arrangement presenting a relatively large mirror surface which during use of the lip stick can be easily held in the correct position, using the casing of the lip stick as a handle for the mirror, while by means of the same locking device both the lip stick carrier and the mirror can be locked in their non-operative positions.

With these and further objects in view, which will hereinafter appear, according to the present invention the casing of the lip stick is provided with a hinged mirror cooperating with the holder of the lip stick in such a manner that in the position of rest the mirror is held in a fixed position at the longitudinal side of the casing while in its operating position the mirror stands off from the casing.

According to a further feature of the invention the mirror is hinged to the closed end face of the casing under spring action.

According to a further feature of the present invention a ring member of the lip stick carrier engages in the position of rest of the mirror a tongue-shaped holding member of the mirror and by rotation is clamped on this holding tongue by means of a wedge surface. To this end, the ring member of the lip stick carrier may possess on its inner side a plurality of wedge-shaped projections in such a manner that the highest wedge point of one of the projections follows the lowest wedge point of the next projection. Advantageously the highest and lowest wedge points of the ring member of the lip stick carrier pass over into each other in the form of waves.

Since the lip stick carrier which is usually a sleeve, must be removable from the casing in an axial direction for using the lip stick, the danger exists that the lip stick may be released undesirably from its closed position and even slip out of the casing if it is not locked in the closed position. Where this happens while the lip stick casing is in a bag or a pocket or the like,

disagreeable spoiling of this bag or pocket may occur. Moreover, the mirror when opened entirely or partly may be caught somewhere and cause injury to the bag or pocket, or the mirror may be broken or its hinge members may be deformed. This danger is reliably removed by further features of the invention relating to a special locking device. To this end, the ring member of the lip stick socket which slightly overhangs the lip stick casing and engages the holding tongue of the mirror is provided with wedge surfaces projecting radially inwards. When the lip stick socket is moved into the casing, the ring member merely has to be turned a little in order to create a jamming or clamping effect such that undesirable loosening or releasing of the locking device cannot happen.

Other and further objects, features and advantages of the invention will be pointed out hereinafter and appear in the appended claims forming part of the application.

In the accompanying drawing a number of preferred embodiments of the invention are shown by way of illustration and not by way of limitation.

Fig. 1 is an axial section of a preferred modification of the assembly.

Fig. 2 is a front view thereof,

Fig. 3 is a top plan view of the sleeve or socket for the coloured pencil, with the casing taken off, and

Fig. 4 is a similar view showing a modified form.

Similar reference numerals denote similar parts in the different views.

Referring now to the drawings in greater detail, it will be seen that number 1 is a casing for the lip stick which encloses the coloured pencil or lip stick 2. The mirror 3 is hinged to the closed end face 6 of the casing 1 by means of a spring-acted hinge 5. As shown in Fig. 6, the mirror 3 is locked in its non-operative position by a locking member 8. The mirror surface in this case faces the sleeve 4. Advantageously the outwardly facing surface (i. e. the back side) of the mirror may be provided with a monogram, or with ornaments or similar designs. It will be seen that the spring-acted hinge 5 is positioned approximately in the middle of the end face 6, the mirror being provided at the movable hinge part 7 at right angles thereto.

In order to use the lip stick or the like, the casing 1 is seized by the left hand and the coloured pencil 2 is drawn out of the casing 1 by the right hand seizing the socket 4. Thus the locking member 8 is disengaged and the mirror 3 swings into its operative position.

3

It will be seen that the bar 2 is surrounded in its non-operative position by a container 1. The bar can be moved longitudinally in a sleeve 11, as by screwing, in a manner known per se, by means of its socket 10. It can thus be moved out of the sleeve 11 according as it is used up, the sleeve 11 formed with a ring member 4 serving as a holder and overhanging the container 1 for some length in the closed position.

The mirror 3 which may be fixed in a suitable frame 12, is hingedly mounted to the end wall 6 of the container 1 by means of the hinge 5 disposed in the middle of the end wall 6. Connected to the hinge part 7 at right angles thereto is the frame 12 bearing the mirror 3.

At its opposite end the mirror 3 or its frame 12 is provided with a tongue-shaped retaining member 8 adapted to be engaged by the ring member 4, if the latter is put on the container 1. In order to prevent the ring member 4 from slipping off in an axial direction, the inner ring 13 of the ring member is provided with wedge-shaped surfaces 14 of Fig. 3 which according to Fig. 4 may be arranged in such a manner that the highest point 15 of one conical surface is followed by the lowest point 16 of the next conical surface.

If after use of the lip stick or the like the sleeve 11 is again put into the container 1, this is effected in such a way that the tongue 8 is located in the zone of the lowest point 16 of the wedge surface. If the ring member 4 is now turned in the direction of arrow X with the sleeve 11 therewithin, the holding tongue 8 is clamped between the wall of the container 1 and the wedge surface, i. e. in the vicinity of the highest points thereof. Therefore, the ring member 4 is prevented from undesirable movement in the direction of arrow Y.

As indicated in Fig. 3, the wedge-shaped clamping surfaces 14 of the ring member 4 can also be arranged in such a way that the highest wedge points 17 and the lowest wedge points 18 pass over into each other in the form of waves. This design offers the advantage that the ring member 4 can be clamped on the holding tongue 8, no matter whether the rotation takes place in the direction of arrow X or in the direction of arrow Z. Accordingly the user of the lip stick need not pay any special attention to the direction of rotation required for achieving the clamping action.

While the invention has been described in detail with respect to certain presently preferred examples and embodiments of the invention it will be understood by those skilled in the art after understanding the invention, that various changes and modifications may be made without departing from the spirit and scope of the invention and it is intended, therefore, to cover all such changes and modifications in the appended claims.

Having thus described our invention, we claim and desire to secure by Letters Patent:

1. A cosmetic implement for a colored pencil comprising a socket in which the pencil is mounted, a casing for said pencil and socket, a mirror hinged to said casing on the outside thereof movable adjacent to and away from the casing and having a tongue-shaped retaining member, and a ring member including at least one internal wedge-shaped portion removably mounted on one end of the casing for engaging said retaining member by the wedge portion and jamming the ring member on the cas-

4

ing by rotation thereof whereby the mirror is retained on the longitudinal side of the casing in its non-operative position but is manually movable away from the casing in its operative position by means of the hinge, and said ring member also retaining the pencil in the casing in the closed position of the implement.

2. A cosmetic implement for a colored pencil comprising a socket in which the pencil is mounted, a casing for said pencil and socket, a mirror hinged to said casing on the outside thereof movable adjacent to and away from the casing and having a tongue-shaped retaining member, and a ring member including a plurality of wedge-shaped internal projections arranged in special relationship relative to each other, said ring member being adapted to be removably mounted on one end of the casing for engaging said retaining member and jamming the same by angular rotation against the casing and is retained on the longitudinal side of the casing in its non-operative position but is manually movable away from the casing in its operative position by means of the hinge, and said ring member also retaining the pencil in the casing in the closed position of the implement.

3. A cosmetic implement for a colored pencil comprising a socket in which the pencil is mounted, a casing for said pencil and socket, a mirror hinged to said casing on the outside thereof movable adjacent to and away from the casing and having a tongue-shaped retaining member, and a ring member including a plurality of wedge-shaped internal projections arranged in spaced relationship relative to each other, said ring member being adapted to be removably mounted on one end of the casing to engage said retaining member and wedge the same against the casing by rotation of the ring member whereby the mirror is retained on the longitudinal side of the casing in its non-operative position but is manually movable away from the casing in its operative position by means of the hinge, and said ring member also retaining the pencil in the casing in the closed position of the implement.

4. A lipstick and mirror combination, comprising a lipstick, a socket in which the lipstick is mounted, a casing for said lipstick and socket, a mirror hinged on the outside of said casing and having a tongue-shaped retaining member, and a ring member including a plurality of wedge-shaped internal projections arranged in spaced relationship relative to each other, said ring being adapted to be removably mounted on one end of the casing to engage said retaining member and wedge the same against the casing by angular rotation of the ring member whereby the mirror is retained on the longitudinal side of the casing in its non-operative position but is manually movable away from the casing in its operative position by means of the hinge, and said ring member also retaining the pencil in the casing in the closed position of the implement.
